DENTAL FLASK CLAMP AND PRESS.

1,412,843.

Specification of Letters Patent. Patented Apr. 18, 1922.

Application filed August 30, 1921. Serial No. 496,985.

To all whom it may concern:

Be it known that we, WALTER J. CLARK and WILLIAM M. ROMINE, citizens of the United States, and residents of Wichita, in 5 the county of Sedgwick and State of Kansas, have jointly invented certain new and useful Improvements in Dental Flask Clamps and Presses, of which the following is a specification.

10 Our invention relates to dental-flask clamps and presses for use in making artificial dentures, and the general object of the invention is to provide a combinable flask-clamp and press having the objects and advantages hereinbelow set forth.

The following, which we consider the ideal requirements for a dental-flask holder or clamp, are filled by our novel flask-holder construction:

20 (A.) Ease of placing and removing flasks, with minimum handling thereof. (B.) Means to hold flasks securely comprising an easily manipulated, positive lock. (C.) Means to apply automatically, first to front

25 of flasks, then gradually to shift the pressure to a point slightly back of centre of flasks, where the full pressure is applied thereto. Thus, the plastic material used to form the anterior portion of the denture is 30 compressed first, thereby preventing other plastic material from impregnating or amalgamating with said anterior material, and eliminating the possibility of the base material of the denture being squeezed into

35 and through the veneering material of the denture. (D.) That the container (clamp) with flasks therein, may be placed in a vessel of boiling water and the denture fully formed, expelling all surplus material (rub-

40 ber) without removing the clamp from such vessel during the operation. (E.) A sufficiently strong spring bearing upon the top of the clamp to allow for expansion and to take up the same during vulcanization.

45 (F.) That the flasks with their enclosed dentures may be placed in, or removed from, a vulcanizer without the operator's touching the flask holder, or, in fact, any metal whatever.

50 The press.

Our improved press is characterized by the following features of both novelty and advantage:

55 This press is constructed with means for engaging it with the top of our improved

flask-clamp, in such manner that the pressure of the press is transmitted to the flasks without the use of a yoke or frame passing beneath the clamp. 60

This press is constructed with a convenient, heat-insulated handle, which, with the press proper, forms a carrier for the flask-clamp.

The press is so constructed that ample 65 pressure may be applied with very little exertion on the operator's part.

Means for instantly disengaging the press from the clamp by simply pressing a button on the handle of the press. 70

By the use of the combination of our improved press and flask-clamp, a saving in time of from 25 to 30 minutes may be effected as compared with the time consumed in using any other flask-press or container 75 of which we are cognizant.

Other advantages, not necessary to discourse upon here, may attach to the constructions and combinations of devices to be described. 80

A preferred embodiment of the invention is represented in the accompanying drawings; but it is to be understood that said drawings are to be construed as illustrative only and not in a limiting sense, as some of 85 the advantages which we have attained may attach to modified constructions not differing in essential features from those shown in these drawings. 90

In the drawings,—

Figure 1 is an elevation of the combined clamp and press, looking into one of the openings of the clamp, showing two empty flasks in position; the press-handle being in section; 95

Fig. 2 is an elevation viewed at right angles to Fig. 1, the lower portion of the clamp being broken away;

Fig. 3 is a detail view in vertical section, of parts to be described;

Fig. 4 is a section viewed on line IV—IV of Fig. 3;

Fig. 5 is an elevation of the combination complete, showing the opposite side of the parts from that shown on Fig. 2; 105

Figures 6 and 7 are fragmentary detail views of the lower portions of the flask holder, Fig. 6 being sectioned upon line VI of Fig. 7, and Fig. 7 being sectioned on line VII of Fig. 6. 110

Describing first the flask holder, or clamp: This part of the apparatus comprises the

curved side walls 1, 2, integral with bottom members 3, 4 respectively. Said bottom members are hingedly connected in a suitable manner: as shown, by tongues 6, on one part, held loosely in openings 7 in the other. Two flasks 7, of the ordinary kind, are held between said walls as shown, the walls extending about an inch above the top of the upper flask. The upper edge 10 of the major wall 1 has an inturned flange 8, which may be undercut, but is not necessarily so. The upper end of wall 2 has a pair of lugs 9, separated by a vertical slot 10. The inner face of each lug 9 has a series 15 of ratchet-teeth 12, the function of which is presently stated.

The wall 1 is provided with a socket-piece 13 (Fig. 3) in which rest pivot-pins 14 on one end of a presser-bar 16, which carries a 20 stiff helical spring 17 and a horizontal plate 18. Spring 17 is housed in a socket, as shown, and bears upon plate 18. The outer end of bar 16 carries a fastening-knob 19 mounted on a rotatable stem 30, locked in 25 place by a collar 21. The width of knob 19 is less than that of the slot 10 between the lugs 9. The outer end of the bar 16 is provided with ratchet-teeth 22 (Fig. 2) adapted to interlock with the teeth 12 of lugs 9. 30 Knob 19 is slidable vertically along the outer faces of said lugs, and also may be turned to a horizontal angle for a fastening purpose.

Plate 18 is loosely supported as follows:— 35 Said plate has a pair of integral upstanding ears 23, in each of which is a small stud 24. Said studs project over the top of bar 16. Each ear 23 is also provided with an arcuate slot 26, having pivots 14 as a centre, and 40 through each slot projects a pin 27, fixedly mounted in bar 16. The lower ends of these slots, as shown, permit the depression of bar 16 relatively to plate 18, whereby spring 17 will be compressed before positive pressure is placed upon said plate.

Each clamp-lug 9 is provided with an opening 27' for the reception of a hook 28 on the lower end of a double latch 29, carried by the press frame, which will next be described.

This frame, as shown, comprises a casting 32 whose shape is clearly disclosed. The lower end of said frame effects engagement with the clamp 1—2 by means of a pair 55 of rigid fingers 33 having lugs 34 secured to the frame proper by screws 36. Said fingers are curved to fit the curvature of clamp wall 1, and are formed with hook flanges 37 adapted for coengagement with flanges 8, 60 as shown. Frame 32 further engages the flask-clamp by means of a depending latch 38, pivotally supported on the frame at 39 for radial motion toward and from the lugs 9. This latch has the hooked ends 28 hereinbefore mentioned. Integral with latch

38 is a release-arm 40, actuated as herein-after stated.

Slidable in a slot 41 in frame 32 is a toggle-block 42, having an upwardly extending guide-pin 43 and a downwardly extending pressure-pin 44. Pin 43 slidably enters a bore 46 in the frame. Pin 44 is of such length as to clear the top of bar 16 when said pin is near the upper limit of its travel and when two filled flasks are within 75 the clamp or holder. Block 42 is connected by pins 47 to a lower pair of toggle-links 48 whose upper ends are connected by pins 49 to a pair of nuts 50, through which extends a right-and-left threaded screw 51, 80 passing rotatably through a suitable bore in the frame, and provided with a non-metallic hand-wheel 52. The upper pair of toggle-links 53 enter slots in the frame and are pivotally connected thereto by pins 54. 85

Mounted on the upper end of said frame is a handle 56, made of some material having low heat-conductivity. By grasping this handle, the operator can handle the entire apparatus, when it is hot, without burning 90 or soiling his hands. This alone is a very desirable feature to mechanical dentists.

Any suitable device for retracting the latch or latches 38, preliminary to attaching the press to the clamp, and for releasing said latch in order to effect disengagement of said parts preliminary to leaving the clamp in a vulcanizer, may be employed. Such device, as shown in the drawing, comprises a lower pull-wire 57, an upper pull-wire 58, 100 a motion-reversing lever 59, a plunger 60, and a spring 61. In detail: said spring is housed as shown in the handle 56; but in practice an equivalent spring may be applied to the lower wire 57, or, more directly, 105 to the latch-arm 40. As shown on Figs. 1 and 5, the lower end of wire 57 is connected to said arm with a nut 62, and said wire passes to the outside of the frame through a groove 63. The upper end of wire 58 is 110 fastened in or to the plunger 60, which projects above the end of the handle. The spring 61 is always under compression, thus exerting always an outward pressure upon the latch 38—28. By depressing the plunger, said latch will be drawn inwardly, causing it to pass easily behind the latch-engaging lugs 9. 115

Our preferred material for all metal parts, is manganese bronze. 120

The method of procedure with our press and flask-holder is, substantially, as follows: When the flasks have been packed they are placed in the clamp, which automatically closes itself into upright position, and the 125 bar 16 is manipulated by its knob 19 to touch the top flask. The plate 18 will now touch only the anterior portion of the upper flask, as both flasks will be held slightly more open at these portions by their contents. The 130

operator grasps the handle 56 and with the thumb depresses the button 60, to retract the latch 38-28; slips the flanges 37 under flanges 8; inserts the hooks 28 in their openings 27, and releases the button 60. After a few turns of the wheel 52 are given to apply pressure through pin 44 to the flasks, the press and the clamp are rigidly fastened together, and can be moved or carried by the handle 56. After the holder has been placed in a vessel of boiling water of a depth sufficient to cover the flasks, and kept there until the plastic material has sufficiently softened, all surplus material will be expelled by the continued pressure of spring 17 upon plate 18 and the flasks, and the flasks will close to the positions shown on our drawings. The press and clamp are then removed from the water, the wheel 52 is given one half-turn backward, to enable the spring 17 to compensate expansion during vulcanization, and the bar 16 is locked in position by turning the knob 19 crosswise, thereby binding the ratcheted parts together. Still using the handle 56, the operator places the clamp in a vulcanizer, and removes the press from the clamp, leaving holder in vulcanizer. After vulcanizing, the press may be re-attached to the clamp for lifting the latter from vulcanizer; the clamp unlocked; and the flasks turned out of same, without touching any metal with the fingers, the narrow section of the clamp turning upon the pivots 6 shown by Fig. 6 and Fig. 7.

It is perhaps needless to explain that while the pressure is being applied to the flasks through the hand wheel, toggles, pin 44, etc., the motion imparted to the presser-bar 16 will slip the ratchet-teeth of said bar past the ratchet-teeth of lugs 9, and the co-engagement of said teeth will hold said bar down to its lowest position, thereby maintaining the required pressure upon the flasks until released.

Though we have referred to a plurality of flasks throughout the description, it is evident that when only one denture is to be vulcanized, an empty flask is inserted above or below the packed flask and the operation will be the same as has been described.

Having thus described our invention, what we claim as new and desire to secure by Letters Patent, is:

- 55 1. In combination, a flask-holder, a superimposed press, means on said holder and press for attaching one to the other, and means actuated from the press for detaching the one from the other.
- 60 2. In combination, a flask-holder, a superimposed press provided with a handle, means on said holder and press for attaching one to the other, and means actuated from the handle of the press for detaching the one from the other.

3. A dental press comprising a screw-and-toggle mechanism, parts actuated through said mechanism for applying pressure to a flask, and means on said press for engaging a flask-clamp, said means being releasable. 70

4. A dental press comprising a handle, a screw-and-toggle mechanism, parts actuated through said mechanism for applying pressure to the top member of a flask-clamp, means on the press for engaging a flask-clamp, and means adjacent to said handle for releasing said clamp-engaging means. 75

5. A press frame, comprising a rigid member for engagement with a flask-clamp, a movable latch also for engagement with a flask-clamp, a spring to actuate said latch, and means carried by the press for retracting said latch. 80

6. A flask-clamp comprising two pivotally connected body sections, a ratchet-toothed lug on the upper end of one section, a presser-bar pivoted at one end on the other section, said bar having ratchet-teeth adapted to engage the aforesaid ratchet-teeth, a plate loosely attached to and below said bar, 90 a compression-spring between said plate and said bar, and means for locking said lug against the toothed face of said presser-bar. 95

7. A flask-clamp comprising two pivotally-connected body sections, a ratchet-toothed lug carried by the upper portion of one section, a presser-bar pivotally attached to the other section of the clamp and extending diametrically across the clamp, said 100 bar having a ratchet-tooth adapted to engage the aforesaid ratchet-teeth, a stem mounted on the toothed end of said bar, and a knob mounted on said stem and adapted to engage the outer face of said lug; one 105 of the last two named parts being rotatable with respect to the presser-bar.

8. A flask-clamp press, comprising a metal frame, a heat-insulated handle upon said frame, means on said frame to engage a 110 flask-clamp, a pivoted latch for engaging a part of a flask-clamp, a spring-extended plunger in said handle, and means actuated by thumb pressure on the plunger, for retracting said latch. 115

9. A flask-clamp press, comprising a metal frame, a screw-and-toggle mechanism, and a member actuated through said mechanism and positioned to bear upon the upper movable member of a flask-clamp of the construction herein described. 120

10. A flask-clamp press, comprising a frame, a screw-and-toggle mechanism for applying pressure to a flask-clamp constructed as herein described, and means on 125 said press for positively engaging a flask-clamp of the kind described; said means being releasable by means comprised within the press.

11. In a combined flask-clamp and press, 130

a clamp comprising side-walls and a bottom, a presser movably mounted at the top of said clamp, a pressure-spring mounted upon said presser and positioned eccentrically 5 with respect to the periphery of the clamp, and a press-actuated member located directly above said spring for transmitting

the pressure through said presser to a flask or flasks within the clamp.
